UNITED STATES PATENT OFFICE.

MICHAL GRABAREK, OF MARQUETTE, MICHIGAN, ASSIGNOR OF ONE-HALF TO SAMUEL NOVAK, OF MARQUETTE, MICHIGAN.

LOCK.

Application filed February 15, 1923. Serial No. 619,153.

To all whom it may concern:

Be it known that I, MICHAL GRABAREK, a citizen of Poland, residing at Marquette, in the county of Marquette and State of Michigan, have invented certain new and useful Improvements in Locks, of which the following is a specification.

This invention relates to certain new and useful improvements in locks, and has particular reference to locks of the type wherein the locking bolt is shifted by a key.

The primary object of the invention is to provide a lock wherein a sliding bolt that is shifted by a key requires several turns or movements of the key in opposite directions to effect the shifting of the bolt to a releasing position.

With the above general objects in view as the nature of the invention is better understood, the same consists of the novel form, combination and arrangement of parts hereinafter more fully described, shown in the accompanying drawings and claimed.

In the drawings, wherein like reference characters designate corresponding parts throughout the several views,

Figure 1 is a top plan view of a lock constructed in accordance with the present invention, the upper wall of the lock casing being removed, and the lock mounted in a supporting structure, as a trunk or the like,

Figure 2 is a top plan view of the lock with the cover plate for the lock mechanism removed showing the key operated shiftable bolt in its locked position and its limit of movement in one direction with the notched positioning arm for the sliding bolt inserted by dotted lines in a shifted position engaged by a key,

Figure 3 is a top plan view of the lock mechanism, similar to Fig. 2 showing the position assumed by the sliding lock bolt upon one rotation of the operating key in a clockwise direction, showing the lock bolt partially released from the keeper member.

Figure 4 is a top plan view, similar to Fig. 3 showing the position of the lock bolt when the operating key has completed two revolutions in a clockwise direction with the lock bolt in engagement with the keeper members,

Figure 5 is a top plan view, similar to Fig. 4 showing the releasing position of the lock bolt accomplished by a single counter-clockwise rotation of the operating key,

Figure 6 is a perspective view of the sliding lock plate or bolt,

Figure 7 is a perspective view of a spring arm associated with the lock bolt.

Figure 8 is a perspective view of the key 60 engaging tumbler that is pivotally and resiliently mounted on the sliding lock bolt,

Figure 9 is a fragmentary perspective view of the notched tensioned arm for retaining the lock bolt in different positions, 65

Figure 10 is a perspective view of the cover plate for the lock mechanism, and

Figure 11 is a side elevational view of a key employed for operating the lock.

Referring more in detail to the accompanying drawing, there is illustrated a lock of the key operated sliding bolt type, the same being adaptable for various uses and herein illustrated in connection with the body portion 1 and cover 2 of the box or trunk. The lock casing is countersunk within the body portion 1 and embodies a bottom plate 3 having an upper edge wall or flange 4 with a removable cover, not illustrated, that is secured in position in the body portion 1 by the cross bolts 5 as clearly illustrated.

The sliding bolt employed in the lock mechanism is shown in detail in Fig. 6 and includes a plate 6 having the lower edge thereof grooved as at 7, forming a depending centrally positioned finger 8 and end arms 9 and 10, the arm 10 carrying a downwardly directed angularly disposed lug 11 clearly shown in Figs. 2 to 5. The bolt body 12 is carried by the upper edge of the plate 6 and carries upwardly directed arms 13, the intermediate and one end arm carrying T-shaped bolt heads 14, while a single inwardly directed bolt head 14^a is carried by the other end arm as clearly shown in Fig. 6.

A depending longitudinally extending rib 15 is carried by the bolt body 12, and when the bolt, as illustrated in Fig. 6 is slidably mounted upon the bottom plate 3 of the lock casing, the rib 15 engages the rib 16 carried by the bottom plate 3 of the lock casing for guiding the movements thereof, the upper edges of the bolt heads 14 and 14^a contacting the flange 4 of the casing plate. 100

A tensioned arm for retaining the sliding lock bolt in its variously shifted positions is disposed within the lock casing, the arm 17 being preferably formed integral with a coil spring 18 at one end thereof that is anchored 110

upon the stud 19 carried by the bottom plate 3 of the lock casing, the tensioned arm 17 being disposed beneath the depending arms 9 and 10 of the locking plate section 6 with the lower edge thereof normally disposed beneath the central finger 8 of the lock plate, as clearly shown in Fig. 4. The lower edge of the tensioned arm 17 adjacent the outer free end thereof is provided with a series of spaced notches 20 and 21, the inner notch 20 being disposed at a greater distance from the adjacent notch 21 than the distance between the notches 21 as clearly illustrated in each of the figures. When the locking bolt is in a locked position at its extreme movement to the left hand side of the lock casing, the depending lug 11 carried by the lock plate arm 10 is received in the notch 20 as shown in Fig. 2.

20 A tumbler 22 of the type best illustrated in Figs. 2 to 5, and 8, is pivotally mounted upon the lock plate arm 10 by a stud pin 23 passing through an opening 24 in the tumbler, and an opening 25 in the arm 10, 25 the tumbler 22 being provided with a key engaging projection 26 and maintained under tension by the arm 27, shown in Fig. 7 as being provided with a notched portion 28 adjacent its lower side to engage the upper side of the tumbler 22, the arm 27 carrying a coiled spring 29 at one end thereof that is anchored upon the stud 30 carried by the lock plate 6 as shown in Figs. 4 and 6.

30 A cover plate 31, shown in Figs. 1 and 10 is provided for the lock mechanism, the same being provided with a key opening 32 and bolt receiving openings 33 for anchoring the same to the bottom plate 3 of the lock casing, the cover 31 being provided 40 with a depending flange 34 upon its upper edge that engages the shoulder 12^a at the lower end of the bolt body 12 that cooperates with the rib and guides 15 and 16 respectively for guiding the sliding movements of the bolt. A keeper plate 35 is carried by the hinged cover 2 and carries depending apertured keeper arms 36 that are projected through openings in the flange 4 when the cover 2 is in a closed position as illustrated.

45 50 In releasing the keeper plate lugs 36 from the bolt heads 14 and 14^a of the lock bolt, when the lock bolt is in the position shown in Fig. 2, the operating key 37 shown in detail in Fig. 9 as being provided with a single lateral ward 38 has the tubular shank thereof received on the centering pin 39, and upon rotating the key in a clockwise direction, the ward 38 will engage the lower edge of the tensioned arm 17 to elevate the 55 same against the tension of the spring 18 to displace the lug 11 from the notch 20, continued rotation of the key placing the ward 38 into engagement with the key engaging end 26 of the tumbler 22, as shown by dotted 60 lines in Fig. 2 for shifting the lock bolt to

the position shown in Fig. 3, the left hand ends of the bolt heads 14 and 14^a still remaining in the apertured keeper lugs 36 with the lug 11 riding upon the free lower edge of the tensioned arm 17 as shown in Fig. 70 3. A second clockwise rotation of the key 37 will cause an elevation of the tensioned arm 17 with the key ward 38 positioned for engagement with the finger 8 of the lock plate for shifting the lock plate and 75 bolt at its limit of movement to the right hand side of the lock casing to position the lug 11 for reception in the outer end notch 21, the bolt head 14^a being displaced from a keeper lug, while the right hand ends of the T-shaped bolt heads 14 are moved into engagement with adjacent keeper lugs. The single counter-clockwise rotation of the key 37 positions the ward 38 for engagement with the arm 9 of the lock plate 6 for 80 shifting the lock bolt to the released position shown in Fig. 5 with the bolt plate lug 11 positioned in the intermediate arm notch 21, the bolt heads 14 and 14^a being then disengaged from the apertured keeper 85 lugs 36 as shown in Fig. 5. It will therefore be seen that in order to release the lock bolt 12 from its keeper, it is necessary to rotate the key 37 in opposite directions thereby rendering the lock more complex in 90 its operation to unauthorized persons attempting to release the same.

95 While there is herein shown and described the preferred embodiment of the present invention, it is nevertheless to be understood that minor changes may be made therein without departing from the spirit and scope of the invention as claimed.

What is claimed as new is:

1. In a lock of the type described, a sliding lock bolt, a keeper therefor, a tensioned arm associated with the lock bolt for retaining the same in different positions, said bolt being constructed whereby sliding movements thereof in opposite directions are required prior to shifting to a released position. 105

2. In a lock of the type described, a sliding lock bolt, a keeper therefor, a tensioned arm associated with the lock bolt for retaining the same in different positions, said bolt being constructed whereby sliding movements thereof in opposite directions are required prior to shifting to a released position, and a key for shifting the bolt. 115

3. In a lock of the type described, a sliding lock bolt, a keeper therefor, a tensioned arm associated with the lock bolt for retaining the same in different positions, said bolt being constructed whereby sliding movements thereof in opposite directions are required prior to shifting to a released position, a key adapted to engage the tensioned arm to release the same from engagement with the 125 130

bolt and engaging the bolt for shifting the same, and a tensioned tumbler carried by the bolt initially engaged by the key for shifting the bolt.

5. In a lock of the type described, a sliding lock bolt, a keeper therefor, a tensioned arm associated with the lock bolt for retaining the same in different positions, said bolt being constructed whereby sliding movements thereof in opposite directions are required prior to shifting to a released position, a key adapted to engage the tensioned arm to release the same from engagement with the bolt and engaging the bolt for shifting the same, a tensioned tumbler carried by the bolt initially engaged by the key for shifting the bolt, and means carried by the bolt adapted to be engaged by the key for reversely shifting the bolt in moving the same to a released position.

5. In a lock of the type described, a sliding lock bolt, a keeper therefor, a tensioned arm associated with the lock bolt for retaining the same in different positions, said bolt being constructed whereby sliding movements thereof in opposite directions are required prior to shifting to a released position, the connection between the tensioned arm and lock bolt including a lug carried by the bolt, and a series of notches in the lower edge of the tensioned arm.

6. In a lock of the type described, a sliding

6. In a lock of the type described, a slid-

ing lock bolt, a keeper therefor, a tensioned arm associated with the lock bolt for retaining the same in different positions, said bolt being constructed whereby sliding movements thereof in opposite directions are required prior to shifting to a released position, the connection between the tensioned arm and lock bolt including a lug carried by the bolt, a series of notches in the lower edge of the tensioned arm, said bolt including a bolt body, spaced bolt arms carried thereby, and transverse bolt heads carried by the outer ends of the arms. 45

7. In a lock of the type described, a sliding lock bolt, a keeper therefor, a tensioned arm associated with the lock bolt for retaining the same in different positions, said bolt being constructed whereby sliding movements thereof in opposite directions are required prior to shifting to a released position, the connection between the tensioned arm and lock bolt including a lug carried by the bolt, a series of notches in the lower edge of the tensioned arm, said bolt including a bolt body, spaced bolt arms carried thereby, transverse bolt heads carried by the outer ends of the arms, and cooperating guide devices for the bolt carried by the bolt and lock casing. 50 55 60 65

In testimony whereof I affix my signature.

MICHAL GRABAREK.
